UNITED STATES PATENT OFFICE.

CHARLES J. GADD, OF LEBANON, PENNSYLVANIA.

RAIL-ANCHOR.

1,116,686.

Specification of Letters Patent. Patented Nov. 10, 1914.

Application filed April 24, 1914. Serial No. 834,640.

To all whom it may concern:

Be it known that I, CHARLES J. GADD, a citizen of the United States, and a resident of Lebanon, in the county of Lebanon and State of Pennsylvania, have invented certain new and useful Improvements in Rail-Anchors, of which the following is a specification.

My invention relates to improvements in rail anchors, or anti-creepers, and the object of my invention is to furnish a rail anchor which can be easily and quickly attached to or detached from a rail, which will be self fastening to the rail, which will grip the rail flange in such a manner as to put it in direct compression, thus eliminating all bending or distortion of the rail flange, and which will coöperate with a cross tie, or some fixed abutment, to effectually restrain and prevent the longitudinal creeping of the rail at right angles to the ties.

My invention is illustrated in the accompanying drawings which form part of this specification, in which similar numerals of reference indicate similar parts throughout the several views, and in which:

Figure 1, is a plan view of part of a cross tie and part of a rail showing my anchor in place upon the rail and engaging the tie: Fig. 2, an end elevation of Fig. 1: Fig. 3, a side elevation of Fig. 2: Fig. 4, an end elevation of the part 1 of the anchor: Fig. 5, an end elevation of the part 2 of the anchor.

My rail anchor consists of two parts 1 and 2 the latter of which is furnished with a curved arm 3 adapted to engage, on its convex side, a fixed abutment, and the former of which carries a part or pin 4 adapted to engage with the concave side of the arm 3 of part 2. The outer ends of parts 1—2 are bent, the first at 5 and the second at 7, upwardly and inwardly to form hooks to engage the sides 6 and 8 respectively, of the rail flange. The upper ends of the hooks 5 and 7 are bent in opposite directions, on a twist, and the bights of the hooks are convexly curved, as shown at 11 on hook 5 and at 12 on hook 7, to facilitate the turning of the parts 1—2 on the edges of the rail flange.

The pin 4 is similarly formed so that it can revolve on the concave side of the arm 3 of the part 2 or so that this concave part of the arm may revolve or turn on the pin, it being evident that whichever one of the parts 1—2 offers the least resistance to the

movement of the rail will be the one that will first turn on or about the pin 4.

When either one of the members 1—2 turns on or about the pin 4 its hooked end, which engages the edge of the rail flange, and which is at its bight convexly curved as previously mentioned, will be moved in the direction of creep of the rail, which is shown by the arrow in Fig. 1, the convexly curved bight rolling upon the edge of the flange of the rail so that the twisted end of the hook will be farther and farther forced upon the flange. As the flange has substantially a wedge shape the farther that the point X of the hook is forced inward upon it the tighter will the hook grasp it. In Fig. 1 of the drawings the part 1 is that supposed to be most loosely connected with the rail flange and the dotted lines show, in an exaggerated manner, the position of the part 1 after its hooked end has been moved forward with the rail. From this dotted position it will be seen that the angular position of the part 1 in relation to the part 2 has been changed with the result that the hooks 5—7 on these parts are more tightly clamped against the flange, as a matter of fact the more the rail creeps the greater will be the angular change between the parts 1 and 2 and the tighter is its flange grasped between the hooks and when these hooks are fully engaged with the flange and the arm 3 of the part 2 is in engagement with a fixed abutment 10, which may be a cross-tie, the creeping movement of the rail is permanently arrested.

If it be the part 2 that is most loosely engaged with the rail flange the hooked end 7 thereof will be moved forward; the concaved side of the arm 3 will turn on the pin 4 as upon a pivot and the convex side of this arm will roll upon the abutment 10 as may be required to adjust itself to the new position of the hook 7, the final result being a change in the angular relation of the parts 1—2, as described in connection with the part 1, which results in the rail flange being firmly engaged upon opposite sides by the hooks 5—7.

With the exception of the upper parts of the hooks 5—7, which engage the upper sides of the rail flange, all parts of the device lie beneath the rail.

To put the parts in place upon a rail the part 1 may be first hooked to the side of the rail

flange after which the arm 3 of the part 2 is passed inside the pin 4 and this arm is moved along the pin until its hooked end 7 engages the part 8 of the flange. A few 5 blows with a hammer will now adjust the two parts to the position shown in Figs. 1 and 2 and any creeping of the rail thereafter will result in it being more tightly grasped between the toggles 1-2. Presently 10 the toggles so tightly grasp the rail flange that any movement of the rail past them is impossible and as the arm 3 of the part 2 is held from movement by the stationary abutment 10 all movement of the 15 rail or toggles is prevented.

The end of the arm 3 of the part 2 is perforated at 13 to pass a spike which may be driven into the tie or abutment 10 to hold this part in place after the arm has been 20 brought to a proper bearing against the tie. This perforation is oblong and the spike is placed at its outer end and is not driven so tightly as to prevent this part from rolling on the tie as the rail creeps and moves the 25 hook 7 in the direction of the arrow, Fig. 1.

Having thus described my invention I claim as new and desire to secure by Letters Patent:—

1. A rail anchor comprising, in combination, a part having at one end a hook adapted to engage one side of a rail flange and at the other a curved arm adapted to engage a stationary abutment, and a part having at one end a hook adapted to engage the other side of a flange and at the other end a bent up portion or pin adapted to engage the curved arm on the other part.

2. A rail anchor comprising, in combination, a member having at one end a hook 40 adapted to engage one side of a rail flange and at the other a curved arm adapted to

engage a stationary abutment, and a member having at one end a hook adapted to engage the other side of a flange and at the other end a bent up portion or pin adapted 45 to engage the curved arm of the first member, the bights of the hooked ends of said members being convexly curved to roll upon the edges of said rail flange and said bent up part or pin of said second member being 50 similarly shaped to roll on the curved arm of said first member.

3. In a rail anchor, in combination, a member hooked at one end to engage one side of a rail flange and furnished at the 55 other end with a curved arm adapted to engage and roll on a stationary abutment, and a member hooked at one end to engage the opposite side of the rail flange and furnished with a bent up portion or pin adapted 60 to be engaged by the concaved side of the curved arm of the other member.

4. In a rail anchor, in combination, a member having at one end a curved arm the convex side of which is adapted to engage 65 a stationary abutment and at the other a hook adapted to engage one side of the flange of a rail, and a second member one end of which is bent to engage the concave side of the arm of said first member, the 70 upper portions of the hooked ends of said members being bent in opposite directions and upon a twist, and the bights of said hooks and the inner side of said pin carried by said second member being convexly 75 curved, all substantially as and for the purposes set forth.

CHARLES J. GADD.
